LITHOGRAPH OFFSET MACHINE
PLATE CLAMP

George P. Daminaitis, Cleveland, Ohio

Application February 25, 1935, Serial No. 8,102

8 Claims. (Cl. 101—415.1)

This invention relates to novel and improved clamping means for securing flexible sheets or plates in even and firm contact with a printing press cylinder, and is particularly adapted for securing the zinc plates to the cylinders of offset lithographing presses.

The main object of the invention is to provide a simple and novel clamp mechanism for such printing plates which will be convenient to operate and which will stand the strain and hold the plate wrapped around the cylinder surface with a uniform tension in all directions so as to prevent any wrinkles on the surface of the flexible plate and insure accurate printing.

15 A further object of the invention is to provide a clamp used as a holder on each of two ends of a lithographic plate for the purpose of attaching the plate around the steel cylinder of a lithographic offset machine.

20 A still further object of the invention is to provide a slot running through the length of the clamp for inserting the lapped end of the plate therein and a series of eyelets at the outward edge of the clamp for engaging the cylinder.

25 A still further object of the invention is to lap the ends of the plate and form a double thickness for locking the ends thereof in the slot of the clamp.

30 A still further object of the invention is to form the clamp in two sections held together by the riveted ends of the eyelets.

35 A still further object of the invention is to form one portion of the slot wider than the other portion to accommodate the double thickness of the lapped end.

A still further object of the invention is to slidably hold the ends of the plate in the clamp.

With the above and other objects in view as will be presently understood, the invention consists in general of certain novel details of construction and combinations of parts hereinafter fully described, illustrated in the accompanying drawing and specifically claimed.

45 In the accompanying drawing, like characters of reference indicate like parts in the several views:

Figure 1 is a view of the completed device comprising the plate with the clamps at the ends.

50 Figure 2 is an enlarged fragmentary view of the clamp and the associated eyelets.

Figure 3 is an end view of the clamp.

Figure 4 is an enlarged sectional view of the clamp showing how the lapped ends of the plate 55 are held in place.

Figure 5 is a fragmentary view of the plate showing the lapped edge.

Figure 6 is a fragmentary view showing the end of the plate attached to the top of the roller of the lithographic machine and

5 Figure 7 is a similar view as Figure 6 but showing the plate attached to the bottom of the roller.

In the embodiment of the invention disclosed in the accompanying drawing there is a plate member 1 to which is applied in the well known 10 manner the characters to be lithographed. The plate is of thin resilient metal and is wrapped around the steel roller 2 of a standard lithograph offset machine. At both ends of the plate are clamps 3 for attaching the ends of the plate to 15 the roller. The roller of a machine of this kind is provided at the top and bottom with the usual fixtures 4 running lengthwise with the roller. Each of these fixtures includes a series of hooks 5 to which the U-shaped eyelets 6 at the ends 20 of the clamp are attached.

The clamp is preferably made from two lengths of material 7 and 8 held together at the ends by the rivets 9. The remainder of the cooperating lengths are held together by the ends 10 of the 25 said eyelets 6. As best seen in Figure 4 the ends of the eyelets are provided with a knee bend and pass through both of the lengths 7 and 8 of the clamp and are riveted in place at the extreme ends as at 11. At the curved portion 30 12 of the eyelets a small amount of solder 13 may be introduced in order to prevent the parts from becoming loose.

In the portion 8 of the clamp a longitudinal slot 14 is provided to hold the end of the clamp. 35 The slot has a widened portion 15 and a narrowed portion 16. The widened portion of the slot is approximately twice the width of the narrowed portion and is adapted to house the lapped end 17 of the plates and the narrow portion is adapted to accommodate the body of the plate. As the width of the narrowed portion is less than the combined thickness of the lapped end 17 of the plate it is obvious that the said end cannot be pulled through the slot. 45

The outward ends of the slots are preferably bevelled as at 18 in order to make the insertion of the plate easier. The plate is in no way fixed to the clamp and can easily be slipped out from the groove.

50 There has thus been provided a simple and efficient device of this kind for the purpose specified.

It is obvious that changes may be made in the form and construction of the invention without 55

departing from the material principle involved. It is therefore not desired to confine the invention to the exact form herein shown and described but it is desired to include all forms which come within the scope of the appended claims.

Having described my invention, I claim:

1. In a device of the class described, a plate adapted to be wrapped around the surface of a roller, said plate having lapped ends, clamps at the ends of said plate, said lapped ends fitting in said clamps, and means to attach said clamps to said roller, said means comprising a set of eyelets at the sides of said clamps adapted to engage a set of hooks on said roller.
2. In a device of the class described, a plate adapted to be wrapped around the surface of a roller, said plate having lapped ends, clamps at the ends of said plate, said lapped ends slidably fitting in said clamps, and means to attach said clamps to said roller, said means comprising a set of eyelets at the sides of said clamps adapted to engage a set of hooks on said roller.
3. In a device of the class described, a clamp provided with a longitudinal slot, said slot having a wide and narrow portion, a set of U-shaped eyelets at the side of said clamp, and a plate fitting at its end in said slot.
4. In a device of the class described, a clamp provided with a longitudinal slot, said slot having a wide and narrow portion, a set of U-shaped eyelets at the side of said clamp, and a plate fitting at its end in said slot, said end of the plate having a thickened portion which fits in the wide portion of the slot.
5. In a device of the class described, a plate adapted to be wrapped around the surface of a roller, said plate having lapped ends, clamps

made of two parts and provided with a slot in one of the parts, said lapped ends fitting in said slot of said clamps, and means to attach said clamps to said roller, said means comprising a set of eyelets at the side of said clamps adapted to engage a set of hooks on said roller, the ends of said eyelets passing through said clamps for holding the parts of the clamp together.

6. In a device of the class described, a plate adapted to be wrapped around the surface of a roller, said plate having lapped ends, clamps made of two parts and provided with a slot in one of the parts, said lapped ends slidably fitting in said slot of said clamps, and means to attach said clamps to said roller, said means comprising a set of eyelets at the side of said clamps adapted to engage a set of hooks on said roller, the ends of said eyelets passing through said clamps for holding the parts of the clamp together.

7. In a device of the class described, a clamp made of two parts, a longitudinal slot in one of the parts, said slot having a wide and narrow portion, a set of U-shaped eyelets protruding outward of said clamp, the ends of said eyelets passing through both of said parts, and a plate fitting at its end in said slot.

8. In a device of the class described, a clamp made of two parts, a longitudinal slot in one of the parts, said slot having a wide and narrow portion, a set of U-shaped eyelets protruding outward of said clamp, the ends of said eyelets being bent, said bent ends passing through both of said parts, and a plate fitting at its end in said slot, said end of the plate having a thickened portion which fits in the said wide portion of the slot.

GEORGE P. DAMINAITIS.
